US00D889754S

(12) **United States Design Patent** (10) **Patent No.:** **US D889,754 S**
(45) **Date of Patent:** **** Jul. 7, 2020**

(54) **HEARING PROTECTOR**

(71) Applicant: **3M INNOVATIVE PROPERTIES COMPANY**, St. Paul, MN (US)

(72) Inventors: **Robert C. Coffin**, Zionsville, IN (US);
Matthew V. Stonebraker, Jr.,
Lafayette, IN (US); **Jacob H. Ely**,
Indianapolis, IN (US); **Ravi Thomas**,
Avon, IN (US)

(73) Assignee: **3M Innovative Properties Company**,
St. Paul, MN (US)

(**) Term: **15 Years**

(21) Appl. No.: **29/721,057**

(22) Filed: **Jan. 17, 2020**

Related U.S. Application Data

(62) Division of application No. 29/616,041, filed on Sep. 1, 2017.

CLAIM

The ornamental design for a hearing protector, as shown and described.

DESCRIPTION

FIG. 1 is a perspective view of a first embodiment of a hearing protector showing our new design;

FIG. 2 is a front view thereof;

FIG. 3 is a back view thereof;

FIG. 4 is a top view thereof;

FIG. 5 is a bottom view thereof;

FIG. 6 is a perspective view of a second embodiment of a hearing protector showing our new design;

FIG. 7 is a front view thereof;

FIG. 8 is a back view thereof;

FIG. 9 is a top view thereof; and,

FIG. 10 is a bottom view thereof.

The broken lines shown in the drawings represent portions of the hearing protector that form no part of the claimed design.

1 Claim, 4 Drawing Sheets
